UNITED STATES PATENT OFFICE.

JULES JOKEL, OF NEW YORK, N. Y.

COMPUTING-TABLE.

1,359,603.

Specification of Letters Patent. Patented Nov. 23, 1920.

Application filed December 30, 1919. Serial No. 348,299.

To all whom it may concern:

Be it known that I, JULES JOKEL, a citizen of the United States, residing at New York, in the county of New York, State of New York, have invented certain new and useful Improvements in Computing-Tables; and I do hereby declare the following to be a full, clear, and exact description of the invention, such as will enable others skilled in the art to which it appertains to make and use the same.

This invention relates to a computing method and table and has for its object the provision of a new method and table for determining easily, quickly and accurately, with little or no mental or manual calculation, the possible selling price or cost price, or other price of any market commodity at any given destination, on the basis of any given cost. The determination of such possible selling price, or cost price, or other price, provides for the inclusion of the freight charges, interest, collection charges, commission, or other charges, together with the cost of insuring the shipment when desired, taking into account the percentage tare which is the expression in per cent. of the ratio of the difference between the gross shipping weight and the net weight of any package or unit to the net weight thereof.

Heretofore it has been customary in the solution of any given problem of this nature, to compute the freight charges on the gross weight or cubic measurement of the unit, together with the cost of insurance or other charges upon the F. A. S. (free alongside ship) cost or F. O. B. (free on board) cost or other cost. This method of procedure may involve four or five, or more separate calculations, as the case may be. It is tedious and laborious and involves the possibility of error in the numerical result through mistakes made in the various steps of the calculation.

In accordance with this invention only a single simple arithmetical addition is required of two figures which are to be found in the computing table. The table may comprise, for convenience, a number of cards, sheets or lists provided with longitudinally arranged rows of series of resultant numbers and at least two columns of index numbers. The simplicity of the method and the facility with which the table may be used is due to the fact that two resultant num-

bers may be utilized in all calculations of possible selling prices or other desired prices for all commodities. One series of the resultant numbers is evolved from and based upon a cost of one cent (\$.01) and an insurance rate of any percentage upon the F. A. S. or other cost valuation. For example, with an insurance rate of one per cent. (1%) upon the usual one hundred and ten per cent. (110%) cost valuation, the constant is computed as follows:

.01 cost.	
1.10	
.0110 basis for insurance—110% cost.	70
.01 insurance rate.	
.000110 cost of insurance.	
.01 cost.	
.010110=cost plus insurance=constant.	75

With this constant as a working basis, a table or tables of resultants may be readily compiled for all F. A. S. or other costs which will serve for all commodities. If the commodity, for example, has an F. A. S. cost of 38¢ the constant .010110 is multiplied by 37 (38 minus unity) and a resultant is thereby obtained for all commodities selling at 38¢ per unit weight or measure.

Another item which enters into the determination of the possible selling price, is the freight rate. For example, let us consider the freight rate of twenty-eight dollars (\$28.00) per ton of two thousand two hundred and forty (2,240) pounds. This is at the rate of one dollar and twenty-five cents (\$1.25) per one hundred (100) pounds. Assuming that the commodity in question is alcohol, which is packed in drums of one hundred and ten (110) gallons each, weighing seven hundred and sixty (760) pounds net and nine hundred (900) pounds gross when packed for shipment, the percentage tare then being equal to

$$\frac{900 - 760}{760} = \frac{140}{760} = 18.4\%.$$

At one dollar and twenty-five cents (\$1.25) per hundred pounds the freight charges on nine hundred (900) pounds is eleven dollars and twenty-five cents (\$11.25) and one hundred and ten per cent. (110%) of eleven dollars and twenty-five cents (\$11.25) is \$12.375. 105 110

The cost of 110 gallons at \$.01 per gallon is \$1.10 and the cost of insurance at one per cent. (1%) is \$.012375, making a total of \$12.48585. To reduce this total to a unit 5 measure basis it should be divided by one hundred and ten (110) there being one hundred and ten (110) gallons in the drum whose net weight is seven hundred and sixty (760) pounds. As a result of this calculation, the resultant .113517 is obtained. If this form of calculation is followed for a 10 freight rate of twenty-nine dollars (\$29.00) per ton, the resultant .117211 will be obtained. The difference between these two 15 resultants is .003694, which is a constant and represents the difference between any two successive freight rates differing by one dollar per ton for a tare of 18.4%.

It will thus be seen that a second series of 20 resultants may be readily evolved which are based upon any given freight rate or other charges for no tare or a definite percentage tare. These resultants may be used in the 25 calculation of the possible selling prices or costs or other prices of all market commodities having the same percentage tare, when the freight rate is any amount per unit of weight or measure.

Not only does this improved method and 30 table provide for fluctuations in the market value of commodities, but it also provides for all possible freight rates, insurance rates, charges, etc. It will thus be seen that the invention comprises the provision of two 35 systems of series of resultant numbers; one series computed on unit cost per unit weight or measure, plus insurance or any other charges on the unit F. A. S. or other valuation, and the other series on unit cost per 40 unit measure or weight, plus freight on unit weight or measure, which includes percentage tare, plus insurance on unit cost valuation. By adding any two of these resultants corresponding to a given cost and a given 45 freight rate, the possible C. I. F. (cost, insurance, freight included) or other price of any market commodity having no tare or a definite percentage tare, may be readily determined.

50 The invention consists further in various details of arrangement of the series of resultants on the computing table, which are described in connection with the accompanying drawing.

55 In the drawing there is illustrated a computing table which may comprise a sheet or card upon which is arranged six columns of resultant figures, and two columns of index figures. The column entitled F. R. 60 (freight rate) represents the index column of freight rates expressed in dollars per ton. The column entitled gallons represents resultants per unit measure for a definite percentage tare (in this case approximately 65 18.4%). The succeeding columns entitled

100 kilograms and hectoliters are obtained by multiplying the resultant numbers as they appear in the unit measure column by factors to change gallons into 100 kilogram units and hectoliters, respectively.

70 The column entitled F. A. S. represents the free alongside ship cost in hundredths of a dollar. The fourth column of resultants entitled gallons, is a series of F. A. S. costs minus unity, per unit measure, plus insurance at unit per cent on 110% F. A. S. cost valuation. As in the case of the second and third columns of resultants, the succeeding columns, the fifth and sixth, involve similar resultants as appear in the fourth and are obtained by multiplying the resultants by factors to change gallons into 100 kilogram units and hectoliters, respectively.

75 The facility and ease with which any problem may be solved by the use of the computing card is well illustrated by the following example: Let the freight rate be twenty-eight dollars (\$28.00) per ton, the commodity be anything having a percentage tare of approximately 18.4% and let the 90 F. A. S. cost be thirty-eight cents (\$.38) per gallon. The problem is; what will be the C. I. F. (cost, insurance, freight, included) price per gallon at a point to which the commodity will be shipped.

95 Let us now refer to the index column F. R. and look opposite the figure 28 and in the first column of resultants entitled gallons. Here we find the numerical resultant .113517. Now referring to the index column entitled 100 F. A. S. cost and opposite the number .38 and in the fourth column of resultants entitled gallons, we find the numerical resultant .374070. Adding the two resultants together we have \$.487587, which is the C. I. F. 105 price per gallon at the desired destination.

110 As a further modification a series of resultants may be compiled for unit measure or weight at various freight rates, but without tare and another series of resultants 110 may be compiled at corresponding freight rates but on a basis of a tare of one per cent. (1%). Thus by adding a resultant for a given freight rate on a basis of one per cent. tare to a second auxiliary resultant for the same freight rate but on a basis of zero tare, a resultant may be obtained for a given freight rate at any particular percentage tare.

115 While this invention has been illustrated and described in connection with a computing table particularly adapted for use in connection with the determination of a cost insurance freight included (C. I. F.) price it is to be understood that the method and computing table may be used for any other purpose for the determination of any desired price, irrespective of whether or not the determination of such particular price requires a rearrangement of the table or a 120

further compilation of resultants which may involve the use of real values for assumed values in any or all of the columns of resultants and I consider such a modification 5 within the broad scope of my invention.

I claim:

1. A computing table for determining the price of a unit weight or measure of any market commodity at any destination including both the cost of the freight and the insurance thereon, comprising a sheet having ruled index columns and rows of numerical resultants thereon, said rows containing numerical resultants based on the 10 cost of the commodity per unit weight or measure at an insurance rate on the cost valuation, and numerical resultants based on unit cost per unit weight or measure at a given freight rate with a percentage tare, all 15 of said columns and rows of resultants being arranged in such relation to each other as to enable the indication of the numerical value of all possible combinations of the numerical resultants for all possible combinations of freight rates and costs.
2. A computing table for determining the price of a unit weight or measure of any market commodity at any destination of

shipment, including both the cost of the freight and the insurance thereon, comprising a sheet, two ruled index columns thereon, one of said columns containing various freight rates successively arranged therein, a longitudinally arranged row of numerical resultants, each of which is based upon a cost of unity per unit weight or measure at a given freight rate for a given percentage tare, and arranged oppositely to the corresponding freight rate in the said index column, the second of said index columns containing various costs per unit weight or measure, and a second longitudinally arranged row of numerical resultants, each of which is based upon a cost of unity and at any rate per cent. of insurance, each of said resultants being oppositely arranged to its corresponding cost, all of said columns and rows of resultants being arranged in such relation to each other as to enable the indication of the numerical value of all possible combinations of the numerical resultants for all possible combinations of the freight rates and costs.

In testimony whereof I affix my signature.

JULES JOKEL.
